UNITED STATES PATENT OFFICE

93,539

DESIGN FOR A DRAPE STAND

Claud C. Colie, Bloomington, Ill.

Application July 17, 1934, Serial No. 52,620

Term of patent 7 years

To all whom it may concern:

Be it known that I, CLAUD C. COLIE, a citizen of the United States, residing at Bloomington, in the county of McLean and State of Illinois, have invented a new, original, and ornamental Design for a Drape Stand, of which the following is a specification, reference being had to the accompanying drawing, forming part thereof.

The figure is a perspective view of a drape stand showing my new design.

I claim:

The ornamental design for a drape stand as shown.

CLAUD C. COLIE,
